CLAIM

The ornamental design for a retail display of electronic devices with graphical user interfaces as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a retail display of electronic devices with graphical user interfaces showing the claimed design.

The broken lines in the FIGURE show portions of the retail display that form no part of the claimed design.
